DESIGN FOR A TOY WASHING MACHINE

Daniel C. Cahalane, Hillsdale, N. J.

Application April 12, 1937, Serial No. 68,683

Term of patent 3½ years

To all whom it may concern:

Be it known that Daniel C. Cahalane, a citizen of the United States and resident of Hillsdale, in the county of Bergen and State of New Jersey, has invented a new, original, and ornamental Design for a Toy Washing Machine, of which the following is a specification, reference being had to the accompanying drawing, forming part thereof, in which, Fig. 1 is a perspective view of my new design for a toy washing machine, and Fig. 2 is an elevational view as seen from the rear side of Fig. 1.

I claim:

The ornamental design for a toy washing machine, as shown.

DANIEL C. CAHALANE.
